DISTORTION-FREE AMPLIFIER CIRCUIT

Horst Tischner, Berlin-Steglitz, Joseph Flurl, Berlin-Karlshorst, and Hermann Wessels, Berlin-Oberschoneweide, Germany, assignors to Allgemeine Elektricitat Gesellschaft, Berlin, Germany

Application September 26, 1936, Serial No. 102,710
In Germany September 30, 1935

1. Claim. (Cl. 179—171)

As is known, in cascade amplifiers, absence of upper harmonics can be attained in a wide degree in that care is taken by suitable choice of the characteristics and working point and proper dimensioning of the coupling members, that the distortions produced in the first tube are just compensated by those produced in the second tube. This is due to the fact that by the first tube a phase rotation of 180° is produced. Thus if the same upper harmonics are produced in both tubes they compensate each other. Already in this way an extensive freedom from upper harmonics is achieved.

The invention is based upon the discovery that hitherto a complete freedom from upper harmonics could not be attained in cascade amplifiers loaded by complex resistances, in view of the fact that the apparent output resistance of the first tube, substantially determined by the coupling members, is practically a purely real resistance, while the apparent output resistance of the end tube is established by the complex resistance and by the coupling members, so that the said output resistance is, as such, a complex resistance. As is known the operating performance at the anode side of a tube loaded by a complex resistance takes the course of an ellipse. The non-linear distortions therefore depend upon the apparent output resistance, and in the first tube which is substantially loaded by a real resistance these non-linear distortions are different from those of the end tube which is substantially loaded by complex resistances. But a prerequisite for a complete compensation is an identical course in the production of upper harmonics.

To obtain a complete compensation the invention provides a circuit in which in the range to be amplified the frequency course of the apparent output resistance of each tube is as nearly the same as possible as regards value and phase. This can be accomplished in various ways. On the one hand, the coupling between the first tube and the second tube can be chosen in such manner that the course of the apparent resistance of the coupling is equal to that of the complex resistance having series-connected coupling elements ahead thereof, such as for instance a cable with transformer in series thereto. On the other hand, the course of the apparent resistance of the cable having a transformer in series, can be so formed by means of additional circuit elements, that it becomes practically a real resistance within the range to be considered, in the same manner as the ordinary capacity

resistance coupling. Finally a compromise can be had between these two possibilities in that on the one hand, the apparent output resistance of the end tube is rendered real as much as possible, and that at the same time, an imaginary component which may still be present, is reproduced in the coupling members between the preliminary tube and the end tube. The frequency course resulting from the entire circuit is eventually freed of distortions by measures taken at the grid of the input tube and which therefore are independent of the compensation.

In the drawing there is shown an example according to the first possibility and an example for the second possibility, whereby Fig. 1 represents a two-stage amplifier cascade, in which the preliminary tube is loaded by an outer resistance, having exactly the same frequency course, and which resistance as regards matching with the preliminary tube is chosen exactly as the output load of the end stage consisting of an output transformer to which a cable is connected. Fig. 2, however, shows an amplifier circuit in which the apparent output resistance of the end tube is rendered real to a wide degree by the addition of circuit elements, such as a condenser.

Fig. 1 shows a two-stage amplifier. The first tube E₁ is coupled to the second tube E₂ across a complex resistance, while the second tube is loaded by a transformer U, at whose secondary terminals there is placed the substitution circuit of the cable, consisting of a capacitive resistance C₁ and ohmic resistance R₁ in series to each other. The output transformer in its substitution circuit consists of a relatively large parallel inductance L₀ and two smaller stray inductances L_{s1} and L_{s2}. This substitution circuit inclusive its capacitance C₂ and ohmic resistance R₁ substituting the cable, serves as coupling resistance between the two tubes. The resistances of the substitution circuit are to be modified eventually according to the ratio between the inner resistances of the tube. Since the grid potential is to be applied to the second tube, a second ohmic resistor R₂ is to be placed in the circuit, and to avoid placing the plate potential at the grid of the second tube, a second condenser C₂ is to be inserted in the circuit. This condenser and the grid resistance must be so dimensioned as regards value that they do not affect the course of the apparent resistance of the substitution circuit. Obviously arrangements could be conceived whereby the substitution circuit as such affords the separation of the

plate potentials, and the application of the grid potentials.

In Fig. 2 there is likewise shown a two-stage amplifier circuit. In this circuit, the coupling 5 between the two tubes E_1 and E_2 is an ordinary capacity-resistance coupling. In order to still obtain practically equal conditions in the apparent resistances in the output of the first tube and in the output of the second tube, there is 10 placed in parallel to the secondary of the transformer U , a correspondingly dimensioned condenser C_3 . Fig. 3 shows the effect of the condenser C_3 upon the course of the apparent resistance of the apparent output resistance of the 15 end tube, measured at the terminals of the primary of the transformer U . The dash curve represents the apparent resistance at different frequencies starting from 1.5 kc. (first point of measurement) up to 5.7 kc. (last point of measurement) whereby the condenser C_3 is omitted. It is seen that the apparent resistance at low 20 frequencies is practically a real resistance, while however with an increase in frequency it has an

imaginary component which steadily increases. The fully drawn curve shows the same mode of measurement whereby however the condenser C_3 is included. The curve has greatly shrunk, the apparent resistance is practically a real one, 5 and independent of frequency.

What we claim is:

A system for the amplification of signals with reduced distortion comprising a pair of vacuum tubes, a load circuit included in the output circuit of each tube, means for coupling the output of one tube to the input of the other, the load circuit in one of said tubes being complex in nature and a function of frequency, and the load circuit of the other tube being a resistance-reactance network arranged to simulate the variation with frequency, both in magnitude and phase, of the impedance of said preceding named load circuit. 10 15
